UNITED STATES PATENT OFFICE.

WALTER B. BRYANT, OF BIRMINGHAM, MICHIGAN.

DESIGN FOR A FURNACE CASING.

Application filed September 24, 1928. Serial No. 28,256. Term of patent 7 years.

To all whom it may concern:

Be it known that I, WALTER B. BRYANT, a citizen of the United States of America, residing at Birmingham, in the county of Oakland and State of Michigan, have invented a new, original, and ornamental Design for Furnace Casing, of which the following is a specification, reference being had therein to the accompanying drawing, forming a part

thereof, in which the figure is a perspective view of a furnace casing showing my new design.

I claim:

The ornamental design for a furnace casing substantially as shown.

In testimony whereof I affix my signature.

WALTER B. BRYANT.
